UNITED STATES PATENT OFFICE.

GEORGE McCaul, of PORTSMOUTH, VIRGINIA.

DESIGN FOR AN EMBLEM, PIN, BADGE, OR SIMILAR ARTICLE.

59,903.

Specification for Design.

Patented Dec. 6, 1921.

Application filed May 23, 1921. Serial No. 471,984. Term of patent 14 years.

To all whom it may concern:

Be it known that I, GEORGE McCaul, a citizen of the United States of America, residing at Portsmouth, in the county of Norfolk and State of Virginia, have invented a new, original, and ornamental Design for an Emblem, Pin, Badge, or Similar Article, of which the following is a specification, reference being had to the accompanying drawing, forming part thereof.

The figure is a view in front elevation of an emblem, showing my new design.

I claim:

The ornamental design for an emblem, pin, badge, or similar article as shown.

GEORGE McCaul.
